UNITED STATES PATENT OFFICE.

MARY NEMEC, OF CHICAGO, ILLINOIS.

KITCHEN-SINK.

1,134,696.

Specification of Letters Patent. Patented Apr. 6, 1915.

Application filed August 8, 1914. Serial No. 855,756.

To all whom it may concern:

Be it known that I, MARY NEMEC, a citizen of the United States, and a resident of the city of Chicago, county of Cook, and 5 State of Illinois, have invented certain new and useful Improvements in Kitchen-Sinks, of which the following is a specification.

My invention relates to improvements in kitchen sinks, and has for its object the production of a sink of the character mentioned 10 which will be better adapted to serve the needs of a sink in the kitchen, a further object being the production of a kitchen sink which will be of a durable and economical 15 construction.

Other objects will appear hereinafter.

With these objects in view, the invention consists in the combinations and arrangements of parts hereinafter described and 20 claimed.

The invention will be best understood by reference to the accompanying drawing forming a part of this specification, and in which,

25 Figure 1 is a front elevation of a kitchen sink embodying my invention, Fig. 2 is a section taken on line $x-x$ of Fig. 1, Fig. 3 is a bottom plan view of one end portion of the sink, and Fig. 4 is a fragmentary perspective view of one of the rear corners of 30 the supplemental shelf of the sink.

The preferred form of construction as 35 illustrated in the drawing comprises a sink consisting of a vertical back portion 1, basin 2 and permanent shelf 3, the portions 1, 2 and 3 being formed integral with each other as is the usual construction.

Arranged at the under side of the shelf 3 40 is a supplemental shelf 4 supported at its lateral edges upon guide flanges 5 formed integral with the shelf 3 and depending from the under side thereof. The inner end of shelf 4 is downwardly offset, as shown, to form a flange 6, and the lateral edges of 45 shelf 4 at the flange 6 are cut away as at 7' in order to permit of the ends 6' of flange 6 engaging under the guide flanges 5, as clearly shown in the several views. With 50 this arrangement, it will be seen that when the shelf 4 is slid forwardly, the outer end thereof will be supported in horizontal position by engagement of the ends 6' of flange 6 against the under side of flanges 5, the 55 possibility of sagging of the outer end of said supplemental shelf being thus precluded.

Formed at the under side of flanges 5 adjacent the forward ends thereof are integral lugs 7 which serve as stops against which the flange ends 6' are adapted to engage in order to limit forward sliding of the supplemental shelf. Threaded in the rearward ends of flanges 5 are screws 8 adapted also for engagement with the flange ends 6' to limit the inward sliding of the supplemental shelf. The screws 8 are inserted or threaded into the flanges 5 after the shelf 4 has been slid to position, said screws, after the same have been secured in position, serving to lock the shelf in position as well as to limit the rearward movement thereof so as to prevent marring or injury of the wall upon which the sink is fastened.

Provided at the periphery of the shelf 4 is an upwardly extending bead 9 which is 75 provided to prevent accidental sliding from said shelf of articles, such as dishes placed thereon. Provided at the under side of shelf 4 adjacent the forward edge thereof is a centrally positioned bead 10 which serves as 80 a finger grip to facilitate outward sliding of said shelf.

The supplemental shelf is provided for employment especially in dish washing. At the present time with sinks provided only 85 with the conventional permanent shelf the dish pan is placed in the basin 2 and the dishes after being washed are arranged upon the shelf 3, being removed from the latter as the same are dried by hand. After being 90 dried there is no convenient place upon the sink where the dishes may be placed, it being necessary to carry the same to some other support such as a distant table or into the pantry or china closet. This results in a 95 considerable waste of time. With the present construction, in the dish washing operation, shelf 4 may be drawn forwardly so as to serve as a support for the dishes after being dried, obviating the necessity of carrying the same to some distant support as is necessary with the conventional sink, as above set forth. When the supplemental shelf is not in use the same may be readily 100 slid to position under the permanent shelf 3 where it will be unnoticed and out of the way. The construction is simple and economical and hence may be manufactured at a low cost.

While I have illustrated and described the 110 preferred form of construction for carrying my invention into effect, this is capable of

variation and modification without departing from the spirit of the invention. I, therefore, do not wish to be limited to the precise details of construction set forth, but 5 desire to avail myself of such variations and modifications as come within the scope of the appended claim.

Having described my invention what I claim as new and desire to secure by Letters 10 Patent is:

The combination with a sink having a permanent shelf, of guide flanges at the under side of said permanent shelf; a supplemental shelf slidably supported by said 15 flanges to permit of said supplemental shelf

being slid forwardly to extend from said permanent shelf; and a downwardly offset flange at the rear end of said supplemental shelf, the lateral edges of said shelf at said flange being cut away to permit of the ends 20 of said flange engaging under said guide flanges, substantially as described.

In testimony whereof I have signed my name to this specification in the presence of two subscribing witnesses.

MARY NEMEC.
